Application January 5, 1940, Serial No. 312,516

28 Claims. (Cl. 196—132)

This invention relates to methods of and apparatus for fluid processing or treating systems, particularly of the forced circulation type wherein in the fluid to be processed or treated is supplied to the inlet of a heated path under pressure and discharges at the other end of the path either as a liquid, a vapor, or a liquid-vapor mixture. Such systems contemplate the generation of steam from water, the processing of petroleum hydrocarbons, or any analogous fluid treating or processing.

While I have chosen to illustrate and describe as a preferred embodiment of my invention the generation of steam in a forced flow vapor generator, it is to be understood that this is by way of example only and that the invention is equally applicable to the processing of petroleum hydrocarbons, or in fact of any fluid in forced circulation through a heated path.

The particular vapor generators here under consideration are of the forced flow type having a fluid flow path including one or more long small-bore tubes, in which the flow in the path is initiated by the entrance of liquid under pressure at one end and the exit of vapor only at the other end and characterized by an inflow of liquid normally greater than the outflow of vapor, the difference being diverted from the path intermediate the ends thereof.

Such a vapor generator, having small liquid storage, and operated with wide range combustion devices, forms a combination rendering practical extremely high heat release rates with the consequent ability to economically handle practically instantaneous load changes from minimum to maximum, and vice versa, without heavy standby expense, and is particularly suitable for operating conditions such as locomotive or marine service where load variations are of a wide range and are required to be met substantially instantaneously.

The generator has a minimum liquid storage capacity with a maximum heat absorbing surface so disposed and arranged as to be substantially instantaneously responsive to rapid changes and wide diversities in heat release rate in the furnace. The heat absorbing surface, or flow path for the working medium, is preferably comprised of a plurality of long small-bore tubes with an enlargement, preferably at the end of the generating

section, which acts as a separator to divide liquid and vapor. The vapor is then passed through a superheater, while the excess liquid carried through the tubes of the generating section for the purpose of wetness and preventing scale deposit, is diverted out of the separator under regulated conditions and is either recirculated to the entrance of the flow path or returned to the hot well or sent to waste. It is usual that a portion of the liquid collected in the separator is sent to waste to keep the concentration below a predetermined value. The diversion or spillover of liquid from the separator is preferably through two paths, either or both of which may be under automatic control comprising a variable or adjustable spillover.

The excess of liquid over vapor generated and which may be completely or partially recirculated, may comprise twenty, thirty, or even fifty percent of the liquid entering the flow path under pressure. The same is true in the case of a processing of petroleum hydrocarbons, in which in fact the percentage by weight of liquid leaving the heated path may be as much or greater than the weight rate of vapor flow.

The separator forms in effect a bulge in the forced circulation path, and is a relatively quiescent zone to which the excess liquid, as well as the vapor, is discharged. In the case of a vapor generator the excess liquid carries the solids from the generating portion of the path to the separator. A portion of the spillover from the separator may be sent to waste or to the hot well or to other apparatus such as a heat exchange. Another portion of the spillover may be recirculated and introduced at the entrance of the generating surface or at the economizer header. It is particularly in the control of such recirculated liquid that I am concerned in the present invention.

Through the utilization of the present invention I am enabled to recirculate a considerable percentage of the liquid entering the flow path and with advantageous results. For example, such recirculation may comprise twenty, thirty, or even fifty percent of the liquid entering the flow path under pressure. So long as such recirculation may be accomplished without loss of heat and without the expenditure of considerable power there are material advantages to be gained thereby.

In a forced circulation type of vapor generator comprising a once through fluid path of one or more long small-bore tubes with a very small liquid storage and a very high rate of evaporation, it is known that the vaporization zone within the path is the location where substantially all of the solids carried by the liquid will be deposited or left in suspension through vaporization of liquid. If not deposited, due to the extreme agitation of the liquid, they will serve to continuously increase the concentration of solids in the liquid remaining in the tube path in and ahead of the vaporization zone. In the separator type of forced circulation boiler with a material excess of liquid inflow to the path over vapor outflow from the path, the economizer and generating section prior to the separator will be at all times wetted to prevent scale formation and will be provided with sufficient liquid to wash all of the solids into the separator. Thus the separator comprises a relatively quiescent zone where separation of vapor and liquid may occur and to which substantially all of the solids of the liquid inflow are carried.

It has been known to continuously divert excess liquid from the flow path at the separator and to discharge such liquid to waste. This means a considerable constant loss of liquid and of the heat contained therein, and the tendency is to reduce the excess liquid to as low a value as possible to save this loss. Preferable operation would be to have a materially greater excess of liquid flowing through the economizer and generating sections than is economically possible if all of the excess is to be discharged to waste from the separator drum.

Such a vapor generator has substantially no heat storage capacity either in the metal parts or in the small volume of liquid stored. It is capable however of very fast changes in heat release and absorption rate. However, through the advantage of my invention, I have been able to materially increase the speed at which load changes may be made through the utilization of the liquid stored in the separator drum at substantially vaporization temperature. Furthermore, I accomplish a recirculation of a very large percentage of the liquid inflow at substantially vaporizing temperature and without an increase in feed pump capacity or power requirements, and in fact under certain conditions of design I have been able to materially reduce the feed pump size or power requirement.

In addition, the invention accomplishes the very necessary desideratum of balancing the plurality of parallel circuits insofar as resistance, flow, temperature and heat are concerned. Through the recirculation of a very large percentage of the liquid inflow the concentrates are diluted and only a small percentage of the spill-over from the separator drum is sent to waste.

In short, I desirably recirculate a higher percentage of liquid inasmuch as no heat is lost and send to waste only a small percentage to blow down the concentrates. I introduce the recirculated liquid into the flow path entrance through the agency of injectors with approximately the same pressure drops as the previously used balancing flow resistors, to serve as circulating pumps to increase the rate of circulation in the vaporization zone without requiring the pumping of extra water by the main feed pump nor the loss of high potential heat occasioned by means of the spillover which formerly must go to the feed water heaters or some similar point of low

heat potential. With a larger percentage of inflow being recirculated instead of to drain, the main feed pump need handle less liquid and require less power.

5 In the multi-circuit path of a forced flow vapor generator it is usual to introduce flow restrictors or equalizers between the economizer and vapor generating sections of the path, to attempt to attain equalization of flow, heating, and other variables through the parallel paths of the generating section, and to prevent overheating of one tube as compared to another. Flow restrictors are usually sections of tubing of relatively small diameter introducing a resistance to flow of several times that of the tube path following, so that variations in flow resistance of said following tube path will be of minimized effect relative to the total resistance including the flow restrictors. Through multiplying the flow resistance several times in this manner it is, of course, necessary to overcome such resistance with feed pump power.

I propose to replace such flow restrictors by injectors inserted in the several tube portions of the path at the entrance to the vapor generating section, utilizing the pressure drop there-through to pump or recirculate the liquid from the separator drum, automatically regulate the supply of liquid to the individual paths, and with 25 the knowledge that such a plurality of injectors will tend to be self-equalizing insofar as heat and flow distribution between the different tube paths is concerned. Any generating tube which has a tendency, due to unequal application of 30 heat for example, to generate more steam than its parallel tubes, tends to become overheated through the presence of generated steam within the tubes rather than a wetting liquid. While the previous flow restrictors or balancing resistors tend to minimize the effect of inequalities 35 in tube resistance, and thereby to equalize flow in the parallel tube circuits, the substitution of an injector for each flow restrictor, with a nozzle resistance commensurate with that of a restrictor, serves not only to retain the advantage of 40 flow equalization but additionally tends toward an equalization of heat, temperature, density, and other properties of the vapor-liquid mixture leaving the tubes.

50 By way of example; should any particular circuit tend to become overheated due either to decrease in flow or increase in heat input (as by localized heating), the pressure drop in that circuit increases due to the increased portion occupied by steam, and this of course may progress until excessive superheating is obtained at the circuit outlet. However, the increased pressure drop of the circuit raises the delivery pressure of the injector and thus decreases its pumping capacity and the amount of recirculated water 55 from the separator drum which enters the circuit. Therefore, the temperature of the mixed feedwater and recirculated water entering this particular circuit is reduced and likewise the tendency toward excessively high ratio of steam to water, or high dry steam temperatures leaving the circuit is checked. Similarly, if a particular circuit receives insufficient heat, a smaller proportion of that circuit will be occupied by steam and the circuit resistance reduced. This results in a decrease in injector delivery pressure and thus an increase in the amount of recirculated water pumped by the injector and entering that circuit. The water withdrawn from 60 the separator drum for recirculating through the

generating portion of the flow path is preferably introduced at the entrance to the generating portion where the temperature of the water coming from the economizer is materially lower than the temperature of the recirculated water. Thus since the net temperature of the water entering the generating portion of the path depends on the ratio of recirculated water to feed water, it is increased and the rate of steaming is accelerated.

Thus the use of injectors in place of balancing resistors tends to automatically balance the tubes in the parallel circuits insofar as flow, heat, temperature, etc. are concerned.

No such heat and/or temperature equalizing tendency is obtained with flow restrictors. When they alone are used, one must depend upon the total resistance, that is, resistors plus tube resistance must be near enough alike in the different circuits to tend to equalize flow therethrough. Through my invention, by the substitution of injectors for flow resistors, there is a greater tendency toward circuit equalization of flow, heat, and temperature, since I have not lost the action of high pressure drop in equalization of flows and at the same time I have gained a tendency toward equalization of fluid thermal conditions leaving the circuits by automatically regulating the feed temperature entering the circuits in an opposite sense to the amount of steam being generated in any particular circuit.

The scheme consists essentially of elimination of the present balancing resistors or flow equalizers and the substitution therefor of injectors with approximately the same pressure drop which will serve as circulating pumps for the individual tube circuits to increase the rate of circulation in the vaporizing zone without requiring the pumping of extra water by the main feed pump. The pressure drop of the present balancing resistors may be used as energy through the injector action to pump at least twenty to thirty percent of the flow rate back from the separator drum to the entrance of the vaporizing section.

It does not appear necessary to go into the reasons for employing a plurality of long small-bore tubes for the forced circulation flow path, inasmuch as the advantage is well recognized in the art. Suffice it to say that having such construction it is of prime importance that the plurality of circuits be equalized insofar as flow, heat, temperature, density, etc. are concerned. The particular features of my present invention to be described and claimed herein relate to the supplying at the entrance of a forced circulation flow path fluid containing liquid in excess of that which will be vaporized during its treatment in the path. In withdrawing near the exit of the treatment zone a flow of liquid, gas, vapor, or a mixture of them, and recirculating it to the entrance or to an early location in the flow path. Thus the fluid passing under pressure through the treatment zone is preferably in part made up of recirculated fluid. It is in the control of the recirculated fluid that my present invention is particularly adapted.

While it is true that I am principally describing my invention in connection with a forced circulation vapor generator, it must be remembered that other treating and processing systems, such for example as the processing of a petroleum hydrocarbon, also employ a plurality of long small-bore tubes for the forced flow path, and here again the necessity of equalization of flow, heat,

temperature, density, etc. is of prime importance. It is not necessary that the forced circulation path either for a vapor generator or for a petroleum processing system comprise a plurality of parallel circuits, but may in fact be a single tube preferably of small bore and great length.

In the drawings in which similar parts bear the same reference numerals

10 Fig. 1 diagrammatically illustrates a drumless forced flow vapor generator to which the present invention is directed.

15 Fig. 2 diagrammatically illustrates the flow circuit of a forced circulation vapor generator embodying the invention.

15 Fig. 3 is similar to Fig. 2 but shows the requisite apparatus to control the functioning thereof, and in partially diagrammatic fashion.

20 Figs. 4 and 5 show portions of a flow path with provisions for flow equalization between parallel circuits.

25 Fig. 6 diagrammatically illustrates an embodiment of my invention particularly adapted to petroleum hydrocarbon treatment.

25 Fig. 7 illustrates the invention applied to a forced circulation fluid path, such as illustrated in Fig. 3.

Fig. 8 is a modification of Fig. 7.

30 The drumless forced flow vapor generator to which the present invention is particularly directed is diagrammatically illustrated in Fig. 1 to indicate gas flow, working fluid flow, and heat absorbing surface, arranged as contained within the enclosure represented by the dot and dash lines.

35 The flow path for the working medium is comprised of long small-bore tubes brought together at suitable headers. The generator includes an economizer 1 at the cooler end of the gas passage and which receives liquid from a pump 30 which may be connected to a hot well. The pump may be of any suitable type or characteristic adapted for the service.

40 The liquid from the economizer outlet header 2 is conveyed by a tube 3 to a manifold 4 from which the liquid is distributed to the generating section through, in this instance, five injectors 5, each of which has a certain resistance drop preferably greater than the particular fluid flow passage which it serves, and whereby the liquid is proportionately distributed to each of the tubular fluid flow passages 6, 7, 8, 9 and 10 constituting the generating section of the assembly which comprises floor, wall, screen and roof portions as indicated.

45 50 55 These five flow circuits comprising the vapor generating surface tangentially enter a bulge in the fluid flow path which is in the form of a separating chamber 11 for dividing the fluid into liquid and vapor, the vapor passing to a superheater 12 and the excess liquid being diverted from the fluid flow path through a pipe 13 to recirculation by means of the injectors or to waste or the hot well.

60 65 70 Through the utilization of injectors between the economizer and generating portions of the path I have made use of the otherwise wasteful pressure loss of the previously known flow equalizers or restrictors. In other words, the injectors of the plurality of circuits would have substantially the same pressure drop as the previously mentioned flow equalizers, but would utilize such pressure drops in actually pumping into the generating section the recirculated spillover from the separator drum. There is thus no extra pump required for the recirculated liquid. There is

substantially no loss in heat in the large volume of recirculated spillover. This recirculated liquid at nearly vaporizing temperature is available at the inlet to the generating section at all times, and as previously brought out is fed proportionate to the rate of operation of the generator as a whole. In other words, as demand upon the generator increases, the injector action will automatically increase, thus drawing a greater volume of recirculated spillover from the separator drum, utilizing the stored liquid thereof, and at no additional pumping expense. The additional volume of highly heated liquid entering the generating section will materially speed up the load-taking-on ability of the generator as a whole. This is further amplified due to the swell of the liquid within the separator when load suddenly increases and pressure on the separator correspondingly suddenly decreases. Such swell or increased volume of liquid within the separator will afford a very welcome additional supply of highly heated liquid to the entrance of the generating section.

Additionally, as previously mentioned, the use of the injectors serves a primary and highly important function in heat and flow equalization between the plurality of circuits as compared to the fixed flow equalizers of prior constructions. Equalization between the various circuits of the generating section will be automatic at times of change in load and self-equalizing to counteract the adverse effects of localized heating or other sources of trouble in operation. Such equalizations will be of flow, temperature, heat, density, etc.

The "heat source" of Fig. 1 is illustrated as having an oil burner 14 supplied by a pipe 15, and controlled by a regulating valve 16. The "heat source" may comprise any well known fuel burning arrangement and have the ordinary provisions for initial ignition, safety features, etc.

In Fig. 1 the spillover pipe 13 has a control valve 17 leading to waste or to the hot well. Branching from the pipe 13 to the recirculating injectors is a pipe 18 having a regulating valve 19, by-passed by a fixed rate of flow by-pass 20.

In Fig. 2 I illustrate diagrammatically the flow path of the working medium without respect to the sequence of heating. The various tubes or parallel circuits of the vapor generating section are brought together and passed as a whole through a pressure differential responsive device prior to entering the separator drum. Certain instruments and regulating valves in connection with the system are shown in Fig. 2 and will be referred to hereinafter in connection with the other figures of the drawings.

It will be understood that any well known form of injector may be utilized in the individual flow circuits and that the particular injector forms no part of the present invention, but will be designed to give desired pressure drop, flow capacity, and characteristics.

It will be further understood that while the vapor generating surface of Fig. 1 is shown as comprising five parallel flow paths, and that of Fig. 2 as comprising two parallel flow paths, these are representative only, and the flow paths may be a single path or any desired number of paths in parallel.

Referring now in particular to Fig. 3 I illustrate the fluid flow path as a single sinuous tube, to the economizer section 1 of which liquid is supplied under pressure through a pipe 21 from a pump 22, which may be of any suitable type, and

which I have therefore illustrated in Fig. 3 merely diagrammatically. From the economizer section the fluid passes to and through the generating section, discharging into the separator 11. From the separator, vapor passes to and through the superheater 12 to a main turbine 23 illustrative of a vapor consuming device. Products of combustion pass successively through the generating section, superheater, and economizer and may 10 contact a part or all of the separator.

An auxiliary turbine 24 drives the liquid feed pump 22, the air blower 25, and the fuel supply pump 26. While I have illustrated these devices diagrammatically and as though all are located 15 to be driven by the same shaft and at the same speed, it will be understood that the necessary gear reduction or driving connections between the several devices are known and would be properly designed as to relative speed, power, etc., and that I merely intend to indicate that the auxiliary turbine 24 drives the devices 22, 25 and 26 simultaneously and in unison.

The rate of supply of fuel oil to the burner 14 through the pipe 15 is primarily controlled 20 by the speed of the oil pump 26, but the supply of oil is further regulated by the throttling of the regulating valve 16.

The rate of supply of air to support combustion is primarily determined by the speed of the 25 blower 25, but is further under the control of a damper 27 positioned at the inlet to the air blower 25.

The rate of supply of liquid under pressure through the conduit 21 is primarily controlled by 30 the speed of the pump 22, but is further influenced through the positioning of a regulating valve 28 at the suction side of the pump.

29 represents means responsive to liquid level within the separator 11 and constitutes a pressure casing enclosing a mercury U-tube connected across the vertical elevation of the separator. A float is adapted to rise and fall with the surface of the mercury in one leg, and to thus cause a positioning of a pointer 30 relative to an index 31 to advise the instantaneous value of liquid level and to further vertically position the stem 32 of a pilot valve 33 to establish one or more air loading pressures representative of liquid level. Such an air loading pressure decreasing 45 with rise in level is transmitted through the pipe 34 to the averaging relay 35. Air loading pressure increasing with rise in level is transmitted through the pipe 36 to a diaphragm actuated valve 17.

50 A rate of flow meter 38 continuously indicates the weight rate of vapor outflow through the conduit 39 and positions a pilot stem 40 in accordance therewith. The air loading pressure representative of weight rate of vapor outflow is effective within a chamber of the averaging relay 35. The averaging relay 35 is connected by means of a pipe 41 with the diaphragm chamber of the valve 28 to position the same responsive both to variations in rate of vapor outflow and to variations in liquid level within the separator 11. For example, liquid inflow is held roughly in proportion to vapor outflow and is readjusted to maintain desirable level within the separator. While the rate of liquid inflow is not entirely under the control of regulating valve 28, it is primarily so, for the pressure drop across the valve 28 is utilized in positioning an auxiliary turbine governor 42.

55 A Bourdon tube 43 is sensitive to vapor outflow pressure and positions a pilot valve 44 to estab-

lish an air loading pressure representative of vapor outflow pressure effective in positioning the damper 21 for readjusting the supply of air for combustion.

The pipe 13 leads from the separator 11 to the regulating valve 17 which latter is under the control of the level responsive device 29. Should level within the separator reach a predetermined high level, the level responsive device 29 will so position the pilot stem 32 that an air loading pressure will be established through the pipe 36 upon the valve 17 and cause the valve to open quickly and in large degree to take care of such emergency conditions until the level is again brought down to below the emergency point.

As previously mentioned, the pipe 18 branches from the pipe 13 and leads to the injector or injectors 5 at the entrance to the generating section. The pipe 18 has a fixed resistance 20 in one branch and a regulating valve 19 in the other branch. As shown, the regulating valve 19 may be positioned in accordance with the loading pressure established by the weight rate of flow meter 38 through the air loading pipe 45 leading from the pilot valve 40. The air loading pressure established by the pilot 40 is normally effective upon the differential relay 35 in conjunction with a loading pressure responsive to separator drum level, jointly, to position the valve 28. By opening valve 46 and closing valve 47 I may make the loading pressure which is representative of weight rate of vapor outflow effective in positioning the regulating valve 19 so that the liquid recirculated to the entrance of the generating section from the separator 11 will vary in accordance with load as represented by the weight rate measure of vapor outflow. This recirculation varying with load is superimposed upon a constant recirculation passing through the fixed resistor 20.

I indicate at 48 an air pressure pipe leading from a pilot valve 49. The air loading pressure established by the pilot 49 is representative of density of the liquid, vapor, or liquid-vapor mixture entering the separator 11 from the generating section of the flow path. Normally the rate of supply of fuel through the valve 16 to the burner 14 is regulated in accordance with such density measurement. However by closing the valve 46 and opening the valve 47 I may additionally place the recirculation valve 19 under the control of the pilot valve 49, or in accordance with density of the fluid entering the separator 11. Thus, I may if desired control either the heating of the path, or the recirculation of working medium, or both, in accordance with density of the fluid entering the separator. Various combinations of such control may readily be obtained by installing the proper valves in the air loading lines 45, 48. I will now describe, with reference to Fig. 3, the arrangement for obtaining an air loading pressure representative of density of the fluid entering the separator 11.

I desire it to be understood that in speaking of density in this description and in the claims I use the term in its well understood and generic definition and meaning, such as has been established by the International Critical Tables, Bureau of Standards, and other authorities as follows:

Density of any substance (a liquid, gas, liquid-gas mixture, or a solid) is expressed in units of weight per unit of volume, as for example, pounds per cubic foot. It is an absolute or concrete

value and therefore quite independent of temperature, pressure, location, etc.

A particular feature of the present invention is a control of the heating and/or of recirculation responsive to a determination of the density of the liquid-vapor mixture leaving the generator section and passing to the separator 11.

In Fig. 3 I have shown a conduit 50 leading from the generating section to the separator 11.

10 In the conduit 50 I have located an orifice or similar restriction 51 which may be a Venturi tube, flow nozzle, or any suitable and well known device for creating a pressure differential representative of the volume rate of flow of fluid 15 therethrough.

Connected to the conduit 50 at opposite sides of the orifice 51, by means of the connecting pipes 52, 53, is a differential pressure responsive device 54 comprising a mercury U-tube on the surface of 20 one leg of which is a float positioned responsive to and representative of the differential in pressure existing across the orifice 51. The float is adapted to position an indicator arm 55 relative to an index 56, and at the same time to position 25 a contact arm along a resistance 57 so that the resistance 57 will be directly representative of differential pressure across the orifice 51.

In similar manner a pressure differential responsive meter 58 is connected across an orifice 30 59 in the liquid feed line 21 and positions a contact relative to a resistance 62. As will be explained hereinafter the resistances 57, 62 comprise legs in a Wheatstone bridge circuit for determining the density of the fluid mixture passing 35 the orifice 51; and such determination of density is utilized in automatically controlling the opening of the fuel regulating valve 16 and/or the recirculation valve 19.

I have also indicated in Fig. 3 a thermocouple 40 T₁ for determining the temperature of the fluid passing through the conduit 21, a thermocouple T₂ sensitive to temperature of the mixture in the conduit 50, and a thermocouple T₃ sensitive to temperature of the steam leaving the superheater 12.

45 As clearly illustrated in Fig. 3, the differential pressure meters 54, 58 are interconnected in a Wheatstone bridge to determine the value of density of the mixture passing through the conduit 50 to the separator 11. I have previously indicated that the resistance values 57, 62 are continuously representative of differential pressure across the orifices 51, 59 respectively.

The relation between volume flow rate and differential pressure is:

$$Q = cM\sqrt{2gh} \quad (1)$$

Where

Q = cubic feet per second

60 c = coefficient of discharge

M = meter constant (depends upon pipe diameter and diameter of orifice hole)

g = acceleration of gravity = 32.17 ft. per sec. per sec.

65 h = differential head in feet of the flowing fluid

The coefficient of discharge remains substantially constant for any one ratio of orifice diameter to pipe diameter, regardless of the density or specific volume of the fluid being measured.

70 With c, M and $\sqrt{2g}$ all remaining constant, then Q varies as the $\sqrt{h}$. Thus it will be seen that the float rise of the meters 54, 58 is independent of variation in density or specific volume of the fluid at the two points of measurement and that

the reading on the indexes 56, 61 of differential head is directly indicative of volume flow rate. If the conduit size and orifice hole size are the same at the two meter locations, then the relation of meter readings is indicative of the relation of density and specific volume. Thus for the same weight rate of flow past the two metering locations, and with a constant water density at orifice 59, the differential pressure at location 51 will increase with decrease in density of the fluid, and vice versa.

This may readily be seen, for if it were desired to measure the flowing fluid in units of weight, Formula 1 becomes:

$$W = cM \times \sqrt{2ghd} \quad (2)$$

Where

W =rate of flow in pounds per second

d =density in lbs. per cu. ft. of the flowing fluid

h =differential head in inches of a standard liquid such as water

M =meter constant now including a correction to bring h of Equation 1 into terms h of Equation 2

Assuming the same weight rate of flow passing successively through two similar spaced orifices 59, 51, and with a change in density of the flowing fluid as may be caused by the heating means, then the density at the second orifice 51 may be determined as follows:

$$\begin{aligned} W_{51} &= W_{59} \\ \sqrt{2gh_{51}d_{51}} &= \sqrt{2gh_{59}d_{59}} \\ \sqrt{h_{51}d_{51}} &= \sqrt{h_{59}d_{59}} \\ d_{51} &= d_{59} \times \frac{h_{59}}{h_{51}} \end{aligned} \quad (3)$$

Thus it will be observed, that knowing the density of the fluid passing the orifice 59 (in this case water), I may readily determine the density of the fluid passing the orifice 51 from the relation of differential pressures indicated by the meters 54, 58.

Referring now to Fig. 3 it will be observed that the adjustable resistances 57, 62 comprise two arms of a Wheatstone bridge. A third arm includes a hand adjustable resistance 63, while a fourth arm includes a fixed resistance 64 and an adjustable balancing resistance 65. The adjustable resistance 65 (for balancing the bridge) is varied by movement of an arm 66, through the agency of a reversible synchronous motor 67, under the control of a galvanometer 68.

The motor 67 is of the self-starting synchronous type of alternating current motor and is shown as having normally deenergized opposed fields. Should the Wheatstone bridge become unbalanced, then the needle of the galvanometer 68 will move either clockwise or counterclockwise, thereby energizing one of the fields of the motor 67, resulting in a positioning of the arm 66 in direction and amount over the resistance 65 to balance the bridge and cause the galvanometer needle to return to neutral position. It will be understood that the necessary gear reduction is incorporated between the motor 67 and the arm 66, so that the arm 66 moves at a relatively slow speed.

The Wheatstone bridge thus serves to continuously determine the density of the fluid at the orifice 51 through solving Equation 3. Such

density is continuously indicated on an index 69 by the movable arm 66.

Solving Equation 3

$$d_{51} = d_{59} \times \frac{h_{59}}{h_{51}}$$

$$\begin{aligned} \text{Resistance } 57 &\propto h_{51} \\ \text{,} & \quad 62 \propto h_{59} \end{aligned}$$

and it is expected that:

10

$$d_{59} > d_{51}$$

$$h_{59} < h_{51}$$

$$R_{62} < R_{65}$$

15 It is known that the law of the Wheatstone bridge is:

$$\frac{R_{62}}{R_{65} + R_{64}} = \frac{R_{57}}{R_{63}}$$

$$R_{65} = \left(R_{63} \times \frac{R_{62}}{R_{57}} \right) - R_{64}$$

and R65 represents d_{51} .

Thus the actual density of the fluid passing through the conduit 50 to the separator 11 is determined and indicated up the index 69. At the same time the arm 66 positions the stem of the pilot valve 49, which may be of the type disclosed and claimed in the patent to Clarence Johnson 2,054,464 and wherein a fluid loading pressure is established in the pipe 48 continuously representative of the value of density of the fluid in conduit 50.

25

It will be understood that each of the temperature responsive thermocouples T_1 , T_2 and T_3 is associated with a known potentiometer device for positioning an indicator relative to an index to advise the value of the temperature, and at the same time to position the stem of a pilot valve, such as pilot 49, for establishing a fluid loading pressure representative of the particular temperature.

30

Under normal conditions of operation variations in vapor outflow effective upon the meter 38 will result in variations of auxiliary turbine speed to proportion liquid inflow, air and fuel to the variations in load. Should level within the separator vary, such changes will also be effective in controlling auxiliary turbine speed, although the magnitude of the changes in auxiliary turbine speed for changes in level may be quite different than the magnitude of changes in auxiliary turbine speed for changes in vapor outflow rate.

35

While in connection with Fig. 3 I have explained in detail the manner in which I determine the density of a liquid-vapor mixture, or in fact of any fluid, I do not believe that it is necessary to repeat such disclosure, either in the other figures of the drawings or in the description pertaining individually thereto. It will thus be understood that insofar as the remaining figures of the drawings are concerned the determination of density may be as explained in connection with Fig. 3.

40

In Figs. 4 and 5 I illustrate a treating zone which may be applicable either to vapor generators or to the processing of petroleum hydrocarbons, or to the treatment of other fluids. Preferably the heated path is comprised of a plurality of parallel circuits, and may include a preheating and a vapor generating or conversion section, although these have not been shown separately. The particular feature of these two drawings is that the recirculation is accomplished by pumps and the distribution to the various

45

50

55

60

70

75

parallel circuits is in accordance with some indication of rate of flow in the separate circuits.

Considering first the disclosure of Fig. 4, I have therein illustrated four parallel circuits (although the number is only representative) all feeding to a relatively quiescent separator zone 11 from which the conduit 39 leads away the vapor and/or gas, while the conduit 13 carries the liquid which has been separated out. Positioned relative to the outflow conduit 39 is a weight rate of flow meter 38 positioning a pilot 40 to establish a loading pressure representative of weight rate of flow of vapor and/or gas passing through the conduit 39. The loading pressure so established is used in controlling a pump 10; as well as an averaging relay 11 in connection with each of the parallel circuits.

In each circuit, near the entrance thereof, I have located an orifice 72 responsive to differential pressure (representative of flow) in the particular circuit, and which differential pressure is effective in the averaging relay 11. A loading pressure established by the averaging relay 11 is effective in positioning a control valve 73 in connection with each of the circuits for controlling the admission of liquid to the circuit from the pump 10.

Thus the arrangement is one wherein the liquid passed to the circuits by the pump 10, is (through the agency of the averaging relays 11) primarily in accordance with the total vapor outflow as measured by the device 38, and secondarily readjusted in accordance with the rate of flow of total fluid entering the heated path in the particular circuit as measured by the orifice 72 of that circuit. Thus the total recirculated liquid is in accordance with vapor outflow measurement and is proportioned to the various circuits in accordance with the rate of flow or differential pressure relation between the circuits.

In Fig. 5 I illustrate only two circuits in the treating zone, but this is representative of any desired plurality of circuits. Herein a rate of flow meter 74 is located in connection with one of the circuits and a rate of flow meter 75 in connection with the other of the circuits. Through differential linkage a pilot stem 76 is positioned to develop an air loading pressure in the line 77 representative of relation between the actual rate of flow in the two conduits to maintain the same in desired proportionality. This air loading pressure in the pipe 77 is used in positioning a proportioning valve 78 which is fed by a recirculating pump 10 and serves to proportion the recirculated liquid to the two circuits of the treating path.

Thus while means are shown in Fig. 4 for readjusting by means of differential pressures, velocities, or volume rate of flow in the various circuits, the apparatus of Fig. 5 utilizes weight rate of flow meters 74, 75 for proportioning the fluid to the circuits on a weight rate of flow basis. In Fig. 5 the pump 10 may be under the control of total load as by a measurement of vapor outflow rate in a manner similar to that illustrated in Fig. 4.

It will further be understood that the arrangement and apparatus as described in connection with the preceding figures, namely, that the plurality of parallel circuits in the treating zone may be brought together prior to entrance into the separator 11, may be applied to the arrangements of Figs. 4 and 5. Furthermore, that the density of the total mixture prior to entering the entering the separator may be determined as

previously described and utilized in similar fashion in connection with the additional apparatus and arrangement of Figs. 4 and 5.

In Fig. 6 I illustrate in diagrammatic fashion the application of my invention to the processing of a petroleum hydrocarbon, as for example in the cracking of oil. Here again in general I illustrate a regulation and proportioning of the feed liquid to the various circuits in the conversion or vaporizing section of the fluid flow path, and furthermore a regulation of the firing in accordance with variables in the operation of the unit. For example, in this drawing, the flow path is divided into a preheating section 79 and a conversion section 80 heated respectively by burners 81 and 82.

A charge liquid enters through a conduit 83 to the preheating section 79 of the flow path which is heated by a burner or burners 81 having fuel controlled thereto by means of a regulating valve 84. The fuel regulating valve 84 is controlled by a fluid pressure established by means of the pilot valve 85 positioned by the potentiometer device 86 sensitive to temperature T_2 of the flowing stream at the outlet of the preheating section.

The heated fluid passes from the section 79 through a conduit 87 having positioned therein an orifice 88 across which is connected a differential pressure meter 89 for positioning a resistance representative of the differential pressure.

The heated petroleum hydrocarbons pass from the conduit 87 to a header feeding to one or more parallel circuits comprising a conversion section 80 heated by a burner or burners 82 to which fuel is supplied under regulated control of a valve or damper 90. The conversion section 80 leads its parallel circuits to a header from which a conduit 91 leads to a tower, reaction chamber, vapor separator, or other relatively quiescent zone 92 where liquids, gases and vapors may separate.

In this particular arrangement the forced flow path is so arranged and proportioned that preferably no vaporization or liberation of gases or vapors occurs in the preheating section 79; and all vaporization or liberation occurs within the conversion section 80. Thus it is normally expected that liquid only will enter the conduit 87 and that a liquid-vapor mixture will leave through the conduit 91 to the vapor separator 92.

The density of the liquid-vapor mixture in the conduit 91 is continuously determined, or a manifestation thereof is determined, through the agency of the differential pressure meters 89, 93, and the Wheatstone bridge measuring system described in connection with Fig. 3. A density determining meter D91 interrelates the resistances positioned by the differential pressure responsive devices 89, 93 to establish a fluid loading pressure effective for control of the fuel supply valve 90 of the conversion section 80.

In such a petroleum hydrocarbon processing system with a mixture of liquid, vapors and gases entering the relatively quiescent zone 92 through the conduit 91 there will be, besides the side cuts or drawoffs of desirable liquids, a discharge of gases and vapors through the pipe 94 near the top of the separator and a discharge of liquid through the conduit 95 near the bottom of the separator.

In the treatment of petroleum hydrocarbons it is often desirable to compose the charge liquid of charging stock with a certain amount of recirculation or recycle from some point in the process beyond the cracking unit or conversion section.

I have shown in Fig. 6 the possibility of introducing a recirculated fluid either to the entrance of the preheating section 79 or to the entrance of the conversion section 80. In the latter event the recirculated fluid is properly proportioned between the various parallel circuits of the conversion section.

I have illustrated the use of injectors as previously described, but additionally it may be necessary to provide pumps such as illustrated at 96 in the various fluid lines to insure a satisfactory pressure of the fluid for entering the conduit to which it is recirculated.

It will be observed that by an arrangement of selective valves I may introduce to the charge liquid of the conduit 83, selectively, either gases and vapors from the conduit 94, liquid from the conduit 95, or a mixture of liquid, gas and vapor from the conduit 91. At the same time, or as desired, I may introduce any of such fluids to the entrance of the conversion section 80 and properly distribute the recycle fluid among the parallel circuits of this section. Additionally the control of recirculation or recycle fluid to either the preheating section or to the conversion section may be regulated in amount or rate of flow either on a volume or a weight rate basis responsive to density d_{91} of the mixture in the conduit 91 in accordance with the disclosure in connection with prior figures of the drawings. It will be understood that the density of the fluid passing through the conduit 91 to the relatively quiescent separating zone 92 bears a relation to the total heat of said fluid so that the processing which occurs within the relatively quiescent zone 92 may be controlled by controlling the heat (through control of the density) of the fluid entering through the conduit 91. Thus utilizing the density d_{91} as an indication of the heat of the fluid entering the chamber 92, I may regulate the heating of the preheating section and/or the conversion section, as well as the composition of the charge fluid entering either or both of these sections.

Fig. 7 is somewhat similar to Fig. 6, except that it relates more particularly to the forced circulation vapor generator of the type previously described in connection with Fig. 3. Herein I illustrate the possibility of recirculation of fluid either to the entrance of the economizer section 1 or to the entrance of the generating section of the vapor generator. This, irrespective as to whether either or both of these sections is comprised of a single tube or of a plurality of parallel circuits. The fluid is introduced to the flow path by means of injectors in the present embodiment, and selectively may comprise spillover liquid from the separator 11 recirculated through the conduit 97, steam recirculated through the conduit 98, or a mixture of liquid and vapor as it enters the separator 11 and recirculated through the conduit 99. I illustrate in this drawing the control of further spillover from the drum 11 by a level indication of liquid within the drum so that there is no danger of the drum filling up and liquid entering the superheater.

The arrangement is further shown to have regulating valves 100, 101 and 102 placed in the conduits 97, 98 and 99 respectively, and positioned in accordance with loading pressures established from a density determination. Thus in Fig. 7, as in Fig. 6, a control of recirculation is had from density, and selectivity as to liquid, vapor, or a liquid-vapor mixture of fluid.

In Fig. 8, which is a portion only of the arrangement of Fig. 7, I illustrate that the recirculated liquid, vapor, or liquid-vapor mixture is under the control of temperature, and this may be as desired either from temperature T_1 , T_2 or T_3 . It is quite possible additionally to so arrange the valves and conduits that one fluid recirculating flow may be under the control of density and another under the control of temperature, or as desired.

It should be quite clear that the invention is equally applicable to the vaporization of water, cracking or other treatment of petroleum hydrocarbons, or the processing of any fluid.

In the processing of petroleum hydrocarbons it will be appreciated that in starting up a cold unit, such for example as is illustrated in Fig. 6, there will be a certain period of time before stable or equilibrium conditions are attained. After 20 the system comes to a state of equilibrium wherein the density d_{91} of the transfer line leading from the conversion section to the relatively quiescent vapor separator or reaction chamber remains substantially constant, and with a relatively constant rate of flow of the charge to the unit, as well as stock characteristic, then the recycle or recirculation flow should be held constant and this can be accurately and satisfactorily controlled from transfer line density, such 30 for example as determined by the device d_{91} . It must be kept in mind (referring particularly to Fig. 6) that while the preheating section 79 is shown as a single sinuous path it may well comprise a plurality of parallel circuits. In the same 35 way the conversion section, which is shown in Fig. 6 as a plurality of parallel circuits, might even be a single sinuous tube.

I have previously mentioned that the density of the fluid mixture passing through the transfer line 91 to the reaction zone 92 is substantially a 40 measure of the heat of the fluid passing therethrough, and thus is representative of a determination or indication of load upon the unit. The particular variables in the operation of 45 such a unit with which I am concerned are those such as pressure, temperature, density, heat, rate of flow, load, etc., and this applies not only to the processing of hydrocarbon petroleums, but also in the vaporization of steam, or in fact in the 50 processing or treating of any fluid to which the present invention is adapted.

While I have illustrated and described certain preferred embodiments of my invention I am not to be limited thereto except by the claims in 55 view of prior art.

What I claim as new, and desire to secure by Letters Patent of the United States, is:

1. The method of operating a forced circulation fluid treating system wherein the entering 60 fluid contains a material percentage of liquid, which includes, heating the treating zone of the forced circulation path to a degree whereby a portion of the entering liquid is vaporized, passing the treated fluid to a relatively quiescent 65 separator zone, recirculating a portion of the treated fluid to the entrance of the treating zone, and varying the percentage recirculated responsive to a density manifestation of the liquid-vapor mixture of the treated fluid.

2. The method of operating a forced circulation vapor generator supplied with liquid under pressure at one end, which includes, heating the vapor generator to a degree whereby a portion of the entering liquid is vaporized, passing the 70 liquid-vapor mixture to a separator zone, recir-

culating a portion of the unevaporated liquid from the separator to the entrance of the flow path, and varying the percentage recirculated responsive to a manifestation of density of the liquid-vapor mixture.

3. The method of operating a vapor generator of the forced flow type having a generating portion, which includes, diverting a material percentage of the liquid from adjacent the vaporization zone of the path, reintroducing the diverted liquid to the generating portion, continuously passing a portion of the diverted liquid, and regulating the flow of the remainder responsive to density of the fluid adjacent the point of diversion of liquid from the path.

4. The method of operating a vapor generator of the forced flow type having a separator between the generating and superheating portions of the flow path, which includes, recirculating a material percentage of the liquid entering the generating portion, and varying the percentage recirculated responsive to density of the liquid-vapor mixture of the fluid entering the separator.

5. The method of operating a fluid treating system wherein a portion of the entering liquid is vaporized, which includes, passing the liquid and vapor mixture to a relatively quiescent separator section, allowing the vapor to separate and pass away, recirculating a portion of the unvaporized fluid to the entrance of the treating zone, and varying the percentage recirculated responsive to a manifestation of density of the liquid-vapor mixture of the fluid.

6. The method of processing petroleum hydrocarbon, which includes, flowing the fluid in a pressure stream through a path of relatively great length and small diameter, heating the path whereby a portion only of the entering liquid is vaporized, passing the resulting liquid-vapor-gas mixture to a reaction chamber wherein the liquid is separated, recirculating a portion of the separated liquid to the entrance of the path, and continuously controlling the recirculation in accordance with a continuous manifestation of density of the fluid mixture entering the reaction chamber.

7. The method of operating a fluid treating system wherein a portion of the entering liquid is vaporized, which includes, passing the liquid and vapor mixture to a relatively quiescent separator section, recirculating a portion of the fluid to the entrance of the treating zone, and varying the percentage recirculated responsive to density of the liquid-vapor mixture of the fluid.

8. The method of operating a fluid treating system wherein a portion of the entering fluid is vaporized, which includes, passing the liquid and vapor mixture to a relatively quiescent separator section, allowing the vapors to separate and pass away, supplying liquid to the system in excess over the vapor rate of discharge, and maintaining the excess constant responsive to density of the liquid-vapor mixture.

9. The method of operating a fluid treating system wherein a portion of the entering fluid is vaporized, which includes, passing the liquid and vapor mixture to a relatively quiescent separator section, allowing the vapors to separate and pass away, supplying liquid to the system in excess over the vapor rate of discharge, and maintaining the percentage excess constant responsive to density of the liquid-vapor mixture.

10. The method of processing a petroleum hydrocarbon, which includes, flowing the fluid un-

der pressure through a confined path comprising a preheating and a conversion section, separately heating the sections of the path, utilizing temperature determination of the fluid leaving

5 the preheating section to regulate heating of that section, recirculating a portion of the treated fluid leaving the conversion section to the entrance thereof, and continuously utilizing continuous density determination of the fluid leaving

10 the conversion section to regulate heating of the conversion section as well as the amount of

15 previously treated fluid recirculated to the entrance of the conversion section.

11. The method of processing petroleum hydro-

15 carbon, which includes, flowing the fluid under pressure through a confined path comprising a preheating and a conversion section, separately heating the sections of the path, passing the liquid-vapor-gas mixture from the conversion

20 section to a reaction chamber constituting a relatively quiescent separator zone, recirculating a portion of the vapors and gas leaving the reaction chamber separator zone to the inlet of the path, and continuously regulating the amount of

25 recirculation in accordance with a continuous determination of density of the fluid leaving the conversion section.

12. The method of processing petroleum hy-

30 drocarbon, which includes, flowing the fluid under pressure through a confined path comprising a preheating and a conversion section, separately heating the sections of the path, passing the liquid-vapor-gas mixture from the conversion section to a reaction chamber constituting a rela-

35 tively quiescent separator zone to effect a separation of the liquid, recirculating a portion of the treated fluid to a selected location in the flow path, and continuously regulating the recirculation rate in accordance with a continuous deter-

40 mination of density of the fluid leaving the conversion section.

13. The method of processing petroleum hy-

35 drocarbon, which includes, flowing the fluid under pressure through a confined path comprising a preheating and a conversion section, separately heating the sections of the path, passing the liquid-vapor-gas mixture from the conversion

45 section to a reaction chamber constituting a relatively quiescent separator zone, recirculating a selected separated fraction of the treated fluid from the reaction chamber to each of a plurality of locations in the treating path, and continuously regulating the percentage recirculated in

50 accordance with a continuous determination of density of the fluid subsequent to the initiation of treatment.

14. The method of processing petroleum hy-

35 drocarbon, which includes, flowing the fluid under pressure through a confined path comprising a preheating and a conversion section having a plurality of parallel paths, separately heating the sections of the path, passing the liquid-vapor-gas mixture from the conversion section to a reaction chamber constituting a relatively

45 quiescent separator zone to effect a separation of the liquid, recirculating a portion of the treated fluid to the entrance of the conversion section, continuously regulating the recirculation rate in accordance with a continuous determina-

50 tion of density of the fluid leaving the conversion section, and utilizing the pressure drop of a portion of each of the plurality of parallel paths of the conversion zone to introduce the recirculated fluid to the paths and to properly proportion its

75 distribution.

15. The method of processing petroleum hydrocarbon, which includes, flowing the fluid under pressure through a confined path comprising a preheating and a conversion section, separately heating the sections of the path, passing the liquid-vapor-gas mixture from the conversion section to a reaction chamber constituting a relatively quiescent separator zone to effect a separation of the liquid, recirculating a selected separated phase of the treated fluid to a selected location in the flow path, and continuously regulating the amount recirculated in accordance with a continuous measurement of density of the treated fluid entering the separator.

16. In combination, a forced circulation fluid treating system having a pressure supply of a selected fluid to be treated to one end of the path and discharging as a liquid-vapor mixture to a relatively quiescent zone at the other end, means for treating the fluid, means determining density of the fluid entering said zone, and means under the control of said means for recirculating fluid from adjacent said zone to a selected location in the flow path.

17. In a petroleum hydrocarbon treating system, in combination, a heated forced circulation path for a selected fluid undergoing treatment, a reaction chamber to which the fluid in the path discharges as a liquid-vapor mixture, measuring means continuously determining density of the liquid-vapor mixture of fluid entering the reaction chamber, and means for recirculating vapors and gas from the reaction chamber to the treating path at a location subsequent to the initiation of treatment, said last named means controlled by said measuring means.

18. In a petroleum hydrocarbon treating system, in combination, a heated forced circulation path for a selected fluid undergoing treatment, a reaction chamber to which the fluid in the path discharges as a liquid-vapor mixture, measuring means continuously determining density of the liquid-vapor mixture of fluid entering the reaction chamber, and means for recirculating liquid from the reaction chamber to the treating path at a location subsequent to the initiation of treatment, said last named means controlled by said measuring means.

19. In combination, a forced circulation fluid treating system including, a flow path to which a selected fluid is supplied under pressure, a separating zone to which the path discharges, heating means for the path, means determining density of the treated liquid-vapor mixture of fluid entering the separator, means for recirculating a portion of treated fluid to a selected location in the flow path, and means controlled by the density determining means adapted to regulate the recirculation.

20. The method of operating a vapor generator of the forced flow type, which includes, passing the fluid successively through a preheating section and a generating section of the path and into a liquid-vapor separator, heating the path, and recirculating fluid from the separator to a selected location in the flow path in accordance with a determination of density of the liquid-vapor mixture of the fluid entering the separator.

21. In combination with a forced flow vapor generator having a preheating and a generating section of the path to which a selected fluid is supplied and connected in series, a separator to which the path discharges, heating means for the path, means recirculating fluid from the separator to a selected location in the flow path, and

means determining density of the liquid-vapor mixture of the fluid entering the separator adapted to control the recirculating means.

22. The method of operating a vapor generator of the forced flow type having a separator between the generating and superheating portions of the flow path, which includes, passing fluid under pressure through a plurality of parallel circuits in the generating portion, recirculating a material percentage of the liquid entering the generating circuits through said circuits, and utilizing flow responsive elements in connection with the individual circuits to proportion the recirculation to the circuits.

23. The method of operating a vapor generator of the forced flow type having a separator between the generating and superheating portions of the flow path, which includes, passing fluid under pressure through a plurality of parallel circuits in the generating portion, recirculating a material percentage of the liquid entering the generating circuits through said circuits, separately measuring the weight rate of flow of fluid through the parallel circuits, comparing such measurements, and using the comparison to proportion recirculated fluid to the parallel circuits.

24. The method of operating a forced circulation fluid treating system comprising a plurality of parallel flow circuits, which includes, supplying fluid under pressure to the entrance of the circuits, heating the circuits, passing the treated fluid to a relatively quiescent separator zone, passing the gas and vapor away and measuring its weight rate of flow, recirculating a portion of the separated liquid to the entrance of the processing zone, separately obtaining a flow indication for each of the plurality of circuits, and using the measurement and the flow indications in proportioning the recirculated liquid to the several circuits.

25. In combination, a vapor generator of the forced flow type having a plurality of tube circuits in the generating portion of the path, a relatively quiescent separator zone following the generating portion, means returning liquid from the separator and introducing it at the entrance of each of the tube circuits, means responsive to load on the unit, means responsive to flow in the individual circuits, and regulating means jointly positioned by said last two named means and adapted to proportion the returned liquid to the several circuits.

26. In combination, a vapor generator of the forced flow type having a plurality of tube circuits in the generating portion of the path, a relatively quiescent separator zone following the generating portion, means returning liquid from the separator and introducing it near the entrance and separately to each of the tube circuits, a rate of flow meter of the vapors leaving the separator, and a pump for forcing the returned liquid into the circuits under the control of said flow meter.

27. In combination, a vapor generator of the forced flow type having a plurality of tube circuits in the generating portion of the path, a liquid-vapor separator to which the circuits discharge, means returning liquid under pressure from the separator to the entrance of the circuits, a pressure differential responsive device for each circuit sensitive to the total fluid flow through the related circuit, and a branch conduit having a regulating valve therein branching the return liquid to each of the circuits, each regulating valve under the control of its related pressure differential responsive device.

28. In combination, a fluid treating system of the type having a plurality of parallel forced circulation tube circuits, a separator to which the tubes discharge, heating means for the circuits, means determining rate of vapor and gas flow from the separator, a pump returning liquid from the separator to the entrance of the circuits,

means sensitive to a flow rate variable for each of the circuits, and means responsive to the flow rate means and to the variable sensitive means continuously proportioning the returned liquid to the circuits.

RAYMOND D. JUNKINS.
